[57] CLAIM

The ornamental design for a parking space marker for holding keys, as shown and described.

DESCRIPTION

FIG. 1 is a top plan view of a parking space marker for holding keys showing my new design;

FIG. 2 is a front elevational view thereof;

FIG. 3 is a right end elevational view thereof;

FIG. 4 is a left end elevational view thereof;

FIG. 5 is a rear elevational view thereof; and

FIG. 6 is a bottom plan view thereof.

The broken line showing of a key ring and metal loop in FIGS. 1 and 2 is for illustrative purposes only.
